UNITED STATES PATENT OFFICE.

WILLIAM R. MILLER, OF BALTIMORE, MARYLAND.

INDICATOR FOR MAGAZINES OF GUNS.

SPECIFICATION forming part of Letters Patent No. 393,653, dated November 27, 1888.

Application filed July 26, 1888. Serial No. 221,063. (No model.)

To all whom it may concern:

Be it known that I, WILLIAM R. MILLER, of the city of Baltimore, and State of Maryland, have invented certain Improvements in 5 Repeating Fire-Arms, of which the following is a specification.

This invention relates to certain improvements in Letters Patent of the United States No. 387,531, granted to me on the 7th day of 10 to August, 1888, for certain improvements in fire-arms, to which reference should be had.

In the invention described and shown in the said Letters Patent I employ a stem situated in the magazine and attached to the magazine-spring, or some device having a movement in common therewith, which projects from the end of the magazine, and by the length of the protruding portion indicates the number of cartridges remaining or contained 20 in the magazine. In the preferred construction shown and described in the said Letters Patent I form the magazine spring in two parts or lengths, and interpose between the two springs a plate, to which the inner end of the indicating stem is attached. By this means I am enabled to reduce the length of movement of the stem at each discharge of a cartridge to less than the length of a cartridge. In other words, by the employment of the 25 two springs, as described, the discharge of a cartridge of, say, two and a quarter inches long, may be made to move the stem endwise only one-tenth or one sixteenth of an inch.

The present invention is for the purpose of 30 adapting the invention described in the said Letters Patent to guns and rifles in which the magazine extends to the end of the barrel, and where it would be objectionable or inconvenient to have an indicating-stem projecting beyond the end of the magazine.

The invention consists, therefore, in employing as an indicator the plate which is interposed between the two parts of the magazine-spring instead of the stem, which is removed, 35 and to admit of this arrangement the magazine is slotted, so that the position of the said plate may be ascertained.

The invention further consists in means whereby the slot in the magazine may be concealed from view and the entrance of dust to the magazine prevented.

In the further description of the said invention, which follows, reference is made to the accompanying drawings, forming a part hereof, and in which—

Figure 1 is an exterior side view of a repeating shotgun embodying my improvements. Fig. 2 is an enlarged central longitudinal section of a part of the magazine of the gun. Fig. 3 is an exterior side view of a part of the barrel and magazine of the gun, also enlarged. Fig. 4 is a cross section of Fig. 3, taken on the dotted line *x x*. Fig. 5 illustrates a modification in the construction of a part of the invention, as hereinafter described; and Fig. 6 is an 65 end view of a portion of Fig. 5. Fig. 7 illustrates a further modification of the invention, as hereinafter specified.

Similar parts of the invention are represented by similar letters of reference in all the 70 figures of the drawings.

Referring to Figs. 1 to 4, inclusive, A, B, and C are respectively the stock, barrel, and magazine of the improved fire-arm. D is the magazine spring, whereby the cartridges or shells *a* are fed from the magazine to the barrel. The magazine spring D is in two parts or lengths, *c* and *d*, the former being, say, one-fifth of the length of the latter. E is a plate interposed between the two parts of the spring, 80 and its faces are preferably made concave to receive the ends of the spring.

F is an indicating-pin projecting from the edge of the plate E through a slot, *e*, in the wall of the magazine. This slot is of such length 85 as will allow the free movement of the said pin F as the spring is compressed or extended.

To prevent entrance of dust to the magazine, I provide the pin F with a plate, G, at its outer end, which is long enough to keep the 90 slot at all times covered. The plate is held to the end of the pin by means of a screw, *f*.

When the magazine is filled with cartridges and the spring D compressed, the shield-plate and pin are forced toward the outer end of the 95 magazine, and as each cartridge is discharged the said pin and its plate move toward the stock of the gun a distance which bears the same proportion to the length of a cartridge as the length of the short spring does to that of 100 both springs.

In Fig. 3 the center of the pin F is taken as

the indicating-point, and the outside of the magazine is marked; but either end of the shield-plate could be used as the indicating-point, if desired. It is evident that the shield-plate can be attached directly to the spring, which in that case would be in one piece; but it is preferred to employ the plate interposed between the two parts of the spring, as shown.

In Figs. 5 and 6 the shield-plate is within the magazine, and consists of two hollow cylindrical extensions of the plate E. A convenient method of marking the shield-plate when it is made in accordance with the design just described consists in forming in the center of the plate, or at some other part of the same, an annular groove, g, which, in conjunction with the marks on the outer surface of the magazine, will indicate the position of the plate E and the number of cartridges contained in the magazine. Fig. 6 is an end view of the plate as constructed in Fig. 5.

In Fig. 7 the numerals are stamped on the shield-plate, which corresponds in construction with the one shown in Figs. 5 and 6, and the magazine is provided with a small opening instead of a long slot, through which the figures may be read.

I claim as my invention—

1. In a repeating fire-arm, the magazine thereof having an opening in the side of its wall, combined with a pin which projects from the said spring or an attachment thereof and through the said opening, and a shield-plate secured to the said pin on the outside of the magazine, substantially as specified.

2. In a repeating fire-arm, the magazine thereof having an opening in the side of its

wall, combined with a magazine-spring in two parts, a plate interposed between the two parts of the said spring, a pin projecting from the said plate and through the said opening in the magazine-wall, and a shield-plate fastened to the end of the said pin, substantially as and for the purpose specified.

3. In a repeating fire-arm, the magazine thereof having an opening in the side of its wall, combined with a magazine-spring in two parts, with a plate interposed between the adjacent ends of the two parts of the spring, and an indicating-pin which projects from the side of the plate and into the said opening, substantially as and for the purpose specified.

4. In a repeating fire-arm, the magazine thereof having an opening in the side of its wall, combined with a magazine-spring in two parts, a plate interposed between the two parts of the said spring, a pin projecting from the said plate and into the said opening, and a shield-plate adapted to cover the said opening and at the same time admit of the movement of the said pin, substantially as and for the purpose specified.

5. In a repeating fire-arm, the magazine thereof having an opening in the side of its wall, combined with a magazine-spring in two parts, a plate interposed between the two parts of the said spring, having an indicating-point, and a shield adapted to keep the said opening at all times closed, substantially as and for the purpose specified.

WILLIAM R. MILLER.
